(57) **CLAIM**

The ornamental design for an energy storage system as shown and described.

DESCRIPTION

FIG. 1 is a top, front and left side perspective view of an energy storage system showing my new design;

FIG. 2 is a bottom, rear and right side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 in FIG. 2; and,

FIG. 10 is an enlarged view of portion 10 in FIG. 2.

The broken lines in the drawings illustrate portions of the energy storage system which form no part of the claimed design.

The dot-dashed lines illustrate the boundary of the enlarged views and form no part of the claimed design.
